UNITED STATES PATENT OFFICE.

ERIC CHARLES BENDYSHE WALTON, OF BOMBAY, INDIA.

SLUICE GATE.

Application filed December 13, 1922, Serial No. 606,673, and in India December 22, 1921.

This invention relates to sluice gates or weirs and more particularly to those employed for the purpose of supplying a canal with water as free as possible from silt. Hitherto attempts have been made to exclude silt by employing a rising and falling sluice over the top of which the water flows. These gates have been to some extent successful in excluding silt but have the disadvantage that they have a bad coefficient of discharge and cause considerable afflux, that is difference in level between the upstream and downstream water, the downstream level or the level in the canal being considerably lower than the upstream level or that of the source of supply. To obtain the desired discharge therefore, it is necessary either to construct the canal at a lower level or to keep the source at a higher level than would otherwise be necessary, as for example in the case of a river, by increasing the height of the dam or sluices across it. It has been found that the employment of broad crested weirs tends to improve the conditions of discharge in many cases owing to the facts that eddy losses are reduced and that under certain conditions during floods such weirs cause little or no afflux.

The object of the present invention is to provide an improved form of broad crested weir in which the afflux is reduced to a minimum while the crest is maintained at such a height as to exclude silt as far as possible, thus considerably improving the conditions governing the discharge flow past the gate or weir.

According to this invention the sluice gate or weir comprises a lower gate member having an inclined guide surface or flap extending therefrom on the downstream side, the gate being vertically adjustable and the inclination of the downstream flap remaining substantially constant and independent of the height of the crest or top of the lower gate member. Preferably, in addition to such downstream flap an upstream guide surface is employed provided with means for adjusting its inclination in accordance with the height of the crest.

With such an arrangement the crest may be maintained at a much higher level than would be the case with a vertical sluice gate giving an equivalent discharge through the same width of opening. The length of the downstream guide surface or flap preferably

bears a definite relation to the depth of water over the crest, when the amount of water passing the crest is at its maximum.

The invention may be carried out in various ways, but in its simplest form the gate or weir comprises two flaps hinged together, the hinge being so shaped as to form a smooth and practically continuous surface with the surfaces of the two flaps. The flaps are so disposed that the hinge forms the crest of the weir, and to produce a comparatively broad crest the hinge is made of large diameter. The upstream flap is pivoted at its lower end to a support in the floor of the channel, and the crest is raised or lowered by rotation about this pivot. Any suitable raising or lowering mechanism may be employed. The downstream flap is maintained at a substantially constant inclination which is independent of the height of the crest. Slopes between 1 in $3\frac{1}{2}$ and 1 in $5\frac{1}{2}$ have been found to give satisfactory results. The inclination may be kept practically constant in any suitable manner as for example by means of a parallel linkage, or by providing curved guides in the walls of the channel in which run projections from the sides of the flap, or by suitable supporting ropes, chains or the like.

The best discharge conditions are obtained when the length of the downstream flap bears a definite relation to the depth of water passing the crest. The length of the downstream flap preferably lies between $\frac{1}{2}H$ and $2H$, where H stands for the depth of the crest measured vertically below the upstream water level when the amount of water passing the crest is a maximum and the crest is at its highest normal working level, the longer lengths being preferable where the gate is required to work with a small head of less than $.15H$ and the shorter lengths being preferable where the gate is only required to work with comparatively large heads of $.25H$ and greater. It would not, however, be convenient in practice to vary the length of the flap when the flow of water varies, and this length is therefore so chosen that under the conditions prevailing when the maximum discharge is needed, this rule is satisfied. When the discharge is less than the desired volume may be obtained by lowering the height of the crest to the required extent. This movement of the crest may be effected automatically if desired,

as for example by employing float-operated raising and lowering mechanism.

Some preferred constructions illustrating the application of the invention in various circumstances are shown diagrammatically by way of example in the accompanying drawings, in which—

Figures 1 and 2 are respectively a vertical section and a plan showing the application 10 of the present invention to an existing gate of known type.

Figure 3 is a modification applicable to the construction of a new gate.

Figure 4 shows another modification. 15 Figure 5 is a view showing details of one form of mechanism which may be employed with a sluice gate according to the present invention, and

Figures 6 and 7 show details of the hinges 20 employed in the construction shown in Figure 5.

Like reference letters and numerals refer to like parts in the various figures.

In Figures 1 and 2, which show the application 25 of the invention to a known type of gate, the river or upstream side of the sluice is shown at A and the canal or downstream side at B. In the construction shown the sluice consists of an upper gate 1 and a lower gate 2, of which the latter, when in its lowered position, rests behind a permanent masonry block 3. The gates are formed by girders 4 carrying a skin plate 5, and their ends slide in guides 6 30 in the piers 7 of the headworks.

When it is desired to take in water past the sluice and at the same time to exclude silt, the lower gate 2 is raised to the position shown in Figure 1. An upstream flap 10 is hinged at 11 to the top of the lower gate 2. The other end of this flap slides on a sill 12 suitably disposed in the masonry on the floor of the channel. On the downstream side of the gate is mounted a second flap 45 13. This downstream flap 13 may be fixed to the lower gate 2 or may be hinged thereto as at 14 so that its inclination may be adjusted through a small angle as may be desired. Thus when the lower gate 2 is in its lowermost position, the upstream flap 10 will lie substantially horizontally, while the downstream flap 13 will lie at the desired angle as indicated at 13^a. The flap 13 may be maintained in its correct position 50 by means of suitable guides in the piers or by supporting tackle or other means.

When the lower gate 2 is raised to exclude silt, for example by means of tackle 2^a, the upstream flap will be drawn up into 60 the position shown in Figure 1 so as to form an upstream approach which will guide the water smoothly and evenly over the top of the gate. The downstream flap 13 will also conform to the movement of the lower gate 2, its outer edge 15 being supported by

tackle 13^a or other means in such a manner as to maintain the desired inclination. The provision of ropes or other raising means for the flap 13 may, however, be found desirable in any case to allow of slight adjustments in its inclination irrespective of the height of the lower gate 2, whereby the correct inclination may be obtained to effect the desired discharge. 70

The outer edge 15 of the skin plate of the downstream flap 13 may be extended and suitably curved off as shown at 16 further to reduce eddy losses, or, if found desirable, the edge of the skin plate may be curved up slightly so as to modify the position of 80 the standing wave C, thus varying the coefficient of discharge.

When the lower gate 2 is raised to its highest position so as to close the sluice 85 altogether, the side edges of the upstream flap 10 may be caused to engage fixed stanching blocks 17 disposed in the piers 7, thereby reducing leakage through the gate.

Figure 3 shows an application of the invention to the construction of a new sluice 90 gate, and the arrangement is in many ways similar to that shown in Figures 1 and 2. In this construction the lower gate 2 is eliminated, and the crest is formed by a member 18 connecting the upstream and downstream flaps 10 and 13 together. This member may take the form of a heavy sill or plate or may merely be a hinge of large diameter connecting the two flaps. The raising and lowering mechanism acts 100 on the crest member 18, which will abut against the upper gate 1 completely to close the channel. Alternatively the arrangement may be such that the crest member can be raised high enough to close the channel 105 without being provided with an upper gate. The general arrangement of the sluice is in other respects very similar to that of the previous construction, except that the masonry block 3 in the floor of the channel 110 is now unnecessary. When the gate is raised to its highest position in this construction, it is important that leakage should be cut off as far as possible, and means may be provided whereby the outer edge 115 19 of this flap is pressed tightly against the sill 12 when the gate is raised.

Figure 5 shows a further modification in which the gate is formed as a float or other rigid body 25 having a suitably shaped upper surface. The body 25 is vertically movable within a recess 26 in the floor of the channel. If the body 25 is formed as a float, mechanism such as tackle 25^b may be provided by which it may be held down to 120 the desired height or may be adjusted according to the discharge required. When, however, the body 25 is not buoyant or is semi-buoyant raising and lowering mechanism 25^a of ordinary type may be employed. 130

With this construction it is possible that the recess 26 may gradually get choked up with silt, and to prevent this openings 28 and 29 may be provided respectively in the 5 downstream and upstream walls of the recess, the latter opening 29 preferably being valve-controlled, so that water may be passed through these openings when desired to flush out the recess 26.

10 The upper surface of the body 25 is formed with two inclined guide surfaces sloping away from the crest respectively on the upstream and downstream sides. An upper gate 1 may be provided, if desired, against 15 which the upper surface of the body 25 may abut, so that the channel may be completely closed, or alternatively the arrangement should be such that the body 25 may be raised sufficiently high to close the channel. 20

Figure 5 shows a simple form of sluice gate employing a downstream flap 13 and an upstream flap 10 the crest being formed by the hinge 31, by means of which the 25 two flaps are connected together. The upstream flap 10 is hinged at 32 to the floor of the channel and the crest of the gate is raised or lowered by rotation about this hinge. The inclination of the downstream 30 flap 13 is maintained constant by means of a parallel linkage formed by the two flaps 10 and 13 and links 33, which are connected to the flap 13 towards its outer end and are pivoted at 34 to the floor of the channel at such a distance from the hinge 32, that they remain substantially parallel to the flap 10 during raising or lowering of the gate. 35

It will be noticed that in this construction, as also in some of the constructions previously described, there is a space below the flaps which is open to the downstream water. Under certain conditions eddies may form under the downstream flap 13 as indicated by the arrows in Figure 3, and these eddies 40 would tend to deposit silt and cause the space to get choked up, thus offering considerable obstruction to the lowering of the gate, at low water levels. To prevent this a further flap 35 is hinged at 36 to the outer 45 end of the flap 13, the lower edge of this flap 35 riding on the surface of the bed of the channel. The lower edge of this flap 35 may be fitted with rollers running in suitable guides, if desired, and separate tackle, 50 such as the rope 37 may be provided by means of which it may be raised or lowered to give access to the underside of the gate to facilitate cleaning or repairs. 55

The accumulation of silt under the gate 60 may be further prevented by sloping the floor of the downstream channel as at 42, and by providing one or more ducts 43 leading from the upstream water through the side walls of the gate to an orifice 44 under the gate. Water can thus be passed 65

into the space under the flaps causing an outward flow through any openings there may be, to flush out the space below the gate, and the inlet opening 45 to the duct or ducts may be provided with a small sluice 70 or valve and a screen.

In this construction the upper gate member is formed as a counterweight 38 connected by a rope or ropes 39 passing over pulleys 40 and 41 to the upstream flap 10 75 near the hinge 31. The channel may be completely closed by raising the flap 10 about its hinge 32 until it abuts against the counterweight 38, which is simultaneously lowered to meet it. The ropes 39 80 which connect the lower gate member to its counterweight 38 may be employed as raising and lowering mechanism, or other known forms of mechanism may be employed for this purpose, as for example suitable gearing for rotating the shaft of the hinge 32 85 to which the upstream flap 10 is connected.

It is important that the hinge 31 between the flaps should be of such a nature as to give a smooth connecting surface. A convenient type of hinge is shown in Figure 6. The surface plate of the upstream flap 10 is curved at its upper end 46, so that it has a cross section in the form of a circular arc. The surface plate of the downstream flap 90 13 is then extended to abut tangentially as at 47 against the arc-shaped end 46 of the upstream flap, the shaft 48 forming the axis of the hinge being supported at the centre of the arc in suitable webs 49 and 50 carried by the flaps. The hinge 36 may also be formed in this manner. 95

A somewhat similar construction may be employed for the hinge 32, by which the upstream flap 10 is connected to a support 105 in the floor of the channel. In this case a plate 51 fixed to the support may abut against the arc-shaped end 52 of the surface plate of the flap 10. Other forms of hinges may, however, be employed if desired. 110

It will be understood that the constructions described are given only by way of example to illustrate various applications of the invention, and the details of construction may be varied within wide limits without departing from the spirit of the invention. 115

What I claim as my invention and desire to secure by Letters Patent is:—

1. A sluice gate or weir, comprising in combination, two members hinged together along adjacent edges to form a crest portion, the other edge of one member being secured adjacent the stream bottom, and means for raising and lowering the crest while maintaining the other member at a constant inclination with the horizontal for all positions of the hinged crest. 120

2. A movable sluice gate or weir, comprising in combination, a structure adapted to be submerged in a flowing body of water and 125

having a crest portion and an inclined downstream guide surface portion extending from the crest, means for raising and lowering said structure while maintaining the downstream guide portion at a substantially constant inclination with the horizontal, the length of said guide portion being made between one-half and two times the height of water measured vertically above the crest when the amount of water passing is a maximum for highest normal working elevation of the crest.

3. A sluice gate or weir, comprising in combination, a support member and a guide member hinged together along adjacent edges to form a crest portion, the other edge of the support member being secured adjacent the stream bottom, and means for raising and lowering the crest while maintaining the guide member at a substantially constant inclination, with the horizontal for all positions of the crest, the length of said guide member being made between one-half and two times the height of water measured vertically above the crest when the amount of water passing is a maximum for highest normal working elevation of the crest.

4. A sluice gate or weir, including in combination a member forming the crest, two inclined flaps hinged to the crest member and extending therefrom respectively on the upstream and downstream sides, a fixed support on the floor of the channel to which the upstream flap is hinged, means for raising and lowering the upstream flap about its hinge, and means for maintaining the inclination of the downstream flap substantially constant as set forth.

5. A sluice gate or weir, including in combination two inclined flaps extending from the crest respectively on the upstream and downstream sides, a hinge connecting the two flaps and forming the crest, a fixed support on the floor of the channel to which the upstream flap is hinged, means for raising and lowering the upstream flap about its hinge, and means for maintaining the inclination of the downstream flap substantially constant, the length of the downstream flap bearing a definite relation to the depth of water flowing over the crest when the amount of water passing the crest is at its maximum as set forth.

6. A sluice gate or weir, including in combination two inclined flaps extending from the crest respectively on the upstream and downstream sides, a hinge connecting the two flaps and forming the crest, means for raising and lowering the crest, links hinged to the downstream flap near its outer edge, and fixed supports on the floor of the channel to which the upstream flap and the links are respectively hinged, these fixed supports being so distanced apart that the links are

maintained parallel to the upstream flap as set forth.

7. A sluice gate or weir, including in combination a member forming the crest, two inclined flaps hinged to the crest member and extending therefrom respectively on the upstream and downstream sides, means for raising and lowering the crest, means for maintaining the inclination of the downstream flap substantially constant, and a third flap hinged to the outer edge of the downstream flap as set forth.

8. A sluice gate or weir, including in combination two inclined flaps extending from the crest respectively on the upstream and downstream sides, a hinge connecting the two flaps and forming the crest, means for raising and lowering the crest, links hinged to the downstream flap near its outer edge, fixed supports on the floor of the channel to which the upstream flap and the links are respectively hinged, these fixed supports being so distanced apart that the links are maintained parallel to the upstream flap, and a third flap hinged to the outer edge of the downstream flap as set forth.

9. A sluice gate or weir, including in combination a member forming the crest, two inclined flaps hinged to the crest member and extending therefrom respectively on the upstream and downstream sides, means for raising and lowering the crest, means for maintaining the inclination of the downstream flap substantially constant, a third flap hinged to the outer edge of the downstream flap, a duct leading from the upstream water to the space below the flaps, and a valve controlling the intake opening to this duct as set forth.

10. A sluice gate or weir, including in combination a member forming the crest, two inclined guide surfaces extending from the crest respectively on the upstream and downstream sides, means for raising and lowering the crest, a counterweight forming an upper gate member against which the crest abuts when in its highest position, and means for maintaining the inclination of the downstream guide surface substantially constant as set forth.

11. A sluice gate or weir, including in combination two inclined flaps extending from the crest respectively on the upstream and downstream sides, a hinge connecting the two flaps and forming the crest, means for raising and lowering the crest, a counterweight forming an upper gate member against which the crest abuts when in its highest position, and means for maintaining the inclination of the downstream flap substantially constant as set forth.

In testimony whereof I have signed my name to this specification.

ERIC CHARLES BENDYSHE WALTON.
